UNITED STATES PATENT OFFICE.

SAMUEL J. KETCHAM, OF BUFFALO, NEW YORK, ASSIGNOR TO ALONZO R. KETCHAM, OF SAME PLACE.

SERVICE-BOX FOR WATER OR GAS PIPES.

SPECIFICATION forming part of Letters Patent No. 372,680, dated November 8, 1887.

Application filed May 19, 1887. Serial No. 238,723. (No model.)

To all whom it may concern:

Be it known that I, SAMUEL J. KETCHAM, a citizen of the United States, residing at Buffalo, in the county of Erie and State of New York, have invented certain new and useful Improvements in Service-Boxes for Water or Gas Pipes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to that class of service-boxes for water and gas pipes which have hinged covers adapted to be locked in position; and such invention consists in a special construction and arrangement of parts, all of which will be fully hereinafter set forth and claimed.

In the drawings, Figure 1 is an elevation, partly in vertical section, of the top of the box and its cover in closed position; and Fig. 2 is a similar view showing the cover raised.

Referring to the drawings, *a* represents the top portion of any service-box of well-known construction, in this instance it being cylindrical in form.

Upon one side of the outer surface of the box *a*, at its upper edge, is the lug *a'*, to which the cover is to be hinged. Upon the inner surface of the box and below its upper edge is a shelf or projection, *a''*, forming a portion of the locking mechanism.

b is the cover, of a greater diameter than the cylindrical box *a*, and having the annular flange *b'*, extending downwardly.

At one side of the cover *b*, and within the annular flange *b'*, is the recess *b''*, within which is loosely pivoted the lug *a'* of the box. Diametrically opposite the recess *b''*, and upon the inner surface of the annular flange *b'*, is the boss or enlargement *b'''*, the inner face of which rests near or against the outer surface of the box when the cover is in closed position, as shown in Fig. 1. The central portion of the cover *b* is sunken, forming the re-

cess *b⁴*, the floor of which is provided with the slot *b⁵*.

c is a catch-plate, cut away upon its under surface to form the recess *c'*, and provided upon the lower edge with a horizontally-extending lip or flange, *c''*.

d is a screw-threaded bolt having a hexagonal or other head, *d'*, by means of which it can be turned. This bolt passes down through the slot *b⁴* in the cover, and engages with a screw-threaded orifice in the catch-plate *c*. After the bolt is placed in position, as described, its lower end, *d''*, is upset to prevent disengagement from the catch-plate.

The catch-plate *c*, when in operative position, lies partially within the channel or recess *b⁶* upon the under surface of cover *b*.

The operation of the parts just described is as follows: To lock the cover firmly upon the box, the bolt *d* is turned by a suitable key in the proper direction, and as the catch-plate *c* cannot turn in the channel *b⁶* it is thus lowered in its bearings the required distance and slid back toward the hinged side of the cover by moving the bolt in the slot *b⁵*. In such extreme position the cover is thrown down, the lip *c''* passing below the shelf *a''* of the box. Now, by sliding the bolt *d* and its attached catch-plate to the other end of the slot *b⁵* the lip *c''* passes under the shelf *a''*, and in such position the bolt *d* is turned in the opposite direction, which serves to raise such catch-plate, causing an upward pressure of the lip *c''* against the under surface of the shelf *a''*, thus firmly locking the cover *b* upon its box *a*. To obtain access to the interior of the box the foregoing operation is simply reversed.

It will be seen that the parts forming the locking mechanism of my improved cover not only possess the requisite strength and durability required, but are susceptible of easy and rapid manipulation.

I claim—

The combination, with the body *a* of the service-box, provided with the interior shelf, *a''*, of the cover *b*, hinged to the box, such cover having its central portion recessed and slotted, as shown, the catch-plate *c*, with the

lip c^2 , adapted for engagement with the under surface of the shelf a^2 , and the tightening-bolt d d' , in screw-threaded engagement with the catch-plate and working loosely in the slot b^5 of the cover, all operating substantially as shown and described.

In testimony whereof I have signed my name

to this specification in the presence of two subscribing witnesses.

SAMUEL J. KETCHAM.
